SPRINKLER HEAD

George E. Kunkle, Jr., Dallas, Tex.
(P.O. Box 8056, Fort Worth, Tex. 76112)

Filed Mar. 29, 1971, Ser. No. 129,309

Term of patent 14 years

Int. Cl. D23—01

U.S. Cl. D23—7

FIG. 1

FIG. 2

FIG. 3

FIG. 1 is a side elevational view of a sprinkler head showing my new design;

FIG. 2 is another side elevational view thereof taken from a position rotated 90° from that of FIG. 1; and

FIG. 3 is a top plan view thereof.

I claim:

The ornamental design for a sprinkler head, as shown.
